UNITED STATES PATENT OFFICE.

THOMAS J. YATES, OF SALEM, MASSACHUSETTS, ASSIGNOR TO YATES MACHINE COMPANY, OF SALEM, MASSACHUSETTS, A CORPORATION OF MASSACHUSETTS.

CARPET-CLEANING MACHINE.

1,199,517.

Specification of Letters Patent. Patented Sept. 26, 1916.

Application filed January 7, 1916. Serial No. 70,868.

To all whom it may concern:

Be it known that I, THOMAS J. YATES, a citizen of the United States, residing at Salem, county of Essex, State of Massachusetts, have invented an Improvement in Carpet-Cleaning Machines, of which the following description, in connection with the accompanying drawings, is a specification, like characters on the drawing representing like parts.

This invention relates to improvements in carpet cleaning machines and is particularly adapted to apparatus for the cleaning of rugs and similar articles.

15 The object of this invention is to provide a simple, efficient and durable instrumentality for expeditiously cleaning carpets, rugs and the like.

Another object is to provide means automatically to remove the articles cleaned from the cleaning means and to carry them to drying or other usual apparatus.

25 A further object is to provide improved means whereby the whole of the article may be cleaned by the operation of the machine.

Other objects of the invention will more fully appear from the following description and the accompanying drawings and will be pointed out in the annexed claims.

30 In the drawings, Figure 1 is a semi-diagrammatic view in side elevation of the cleaning machine; Fig. 2 is a sectional view on the line 2—2 of Fig. 1; Fig. 3 is an enlarged detail of the leader disengaging mechanism at the moment of disengagement; and Fig. 4 is a detail of the leader and attached fabric showing the rug attached to the latter. Fig. 5 is a plan view of that part of the machine shown in Fig. 3.

40 The apparatus shown in the drawings of this selected embodiment of the invention substantially comprises a rotating cylinder, around which is drawn the rug or other article to be cleaned, while coincidentally, 45 brushes, revolving in a direction the reverse of that of the cylinder, bear against the article. The face of the rug or carpet is outwardly presented in its traverse of the cylinder so that the brushes properly may exercise their cleaning function.

Heretofore, carpets, rugs and similar articles, have been attached to the moving parts of cleaning machines so that the forward end is not cleaned, necessitating an additional operation to cleanse properly such part subsequent to removal from the ma-

chine. Or, if stitched to a short piece of fabric in turn secured to the machine, the stoppage of the machine is entailed for the manual separation and removal of the article from the leader fabric after the article is started through the machine. Herein is provided, not only an apparatus which permits the thorough cleaning of the entire body of the article, but which also functions automatically to draw the whole body of the article through the cleaning portion of the machine and to carry the cleaned article therefrom to a suitable receptacle or to the usual drier. In this preferred form of the device, a hollow cylinder 1, having its axle 2 suitably journaled in the frame 3 of the machine, is employed. This cylinder is rotatably actuated from a suitable power source through any of the common transmission media, such as, for example, belt and pulley, gear train, etc. The periphery of the cylinder is transversely recessed, a single recess 4 being shown. A leader 5, preferably rigid, such as a wooden or metallic rod, is receivable within this recess and its ends project slightly therebeyond. It is through the medium of this rod and groove engagement that the article to be cleaned is drawn partly around the cylinder in contact with the cleaning media. The cleaning media preferably employed in this machine comprises brushes 10, journaled in the machine frame and rotarily actuated in a direction reverse to that of the cylinder. These brushes are so arranged that they brush the surface of the carpet or rug on the cylinder. These brushes may have associated therewith cleaning fluid receptacles of the type common in this art and therefore not shown. The end of the rug or carpet is connected to this leader 5 and, in order that the end of the rug or carpet may be presented to the cleaning means equally with the whole body of the article, a fabric 6 is suitably secured to the leader 5 as by stitching. The end of the article to be cleaned, herein illustrated as a rug 7, is detachably fastened to this fabric 6 as by stitching. Obviously, a plurality of articles may be fastened to the fabric and so be run through the machine together. The rug 7 is preferably placed upon a support, such as a table 8, having a suitable take-off provided by the over-hanging top 9 which downwardly curves adjacent the cylinder.

In order securely to retain the leader

within the recess during its traverse with the cylinder, a novel locking or latching means is employed. It is preferable that this latching means should be so constructed as to be automatically tripped and unlatched at a predetermined point as to permit the removal of the leader and attached rug. For this purpose, preferably, a latching means is carried by the cylinder on each end face, adjacent each end of the transverse recess 4. As these latching means are substantially similar, one only is necessary to be shown or described. Each, in this preferred embodiment, comprises a plate 11 secured to the cylinder end as shown. This plate 11 has integral upstanding ears 12 at each end. The latch 13 is slidably mounted in apertures through each ear. The collar 14 is fixedly secured to the latch 13 and comprehended between the collar 14 and the lower ear 12 is a means for normally holding the latch in uppermost position, such as a coiled spring 15. The normal position is indicated in Fig. 1. The latch, in this position, projects across the end of the recess 4 and these similar opposed latches function to retain the inserted leader in position in the transverse recess.

Means for removing the rug or other article from the cleaning cylinder and for transferring it readily to the drying or other carrying apparatus is provided. While not essential to the operativeness of this machine, it is decidedly preferable in the interests of economy and efficiency that this removing and transferring mechanism be automatic. And, in order that a substantially continuous and positive feed or pull of the rug through the machine be afforded, there is preferably provided an instrumentality automatically to engage the leader upon its removal from the cylinder. This removing and transferring means comprises primarily, a leader release, a receiving medium and a carrier co-operating with the latter to carry the leader with its attached rug from the cylinder and thereby to draw the remainder of the rug through the cleaning portion of the machine. In this selected embodiment each latching member is provided with a lever 16 pivotally mounted on a downward extension 17 of the plate 11. The link 18 is pivotally secured at one end to the lever 16 and at its other, or upper end is pivotally secured to the collar 14 of the latch 13. The normal position of this lever 16 is that shown in Fig. 1 wherein it is disclosed in a position substantially at a right angle to the position assumed by the link 18. This position of the lever 16 permits the latch to close the recess end and to retain the leader therein. The maximum inner position of the link 18 is determined by the stud 19 on the plate 11. A simple means of tripping each of the thus-project-

ing levers 16 is provided by the trip 20 formed by an arm projecting from a standard 21. The trips 20 engage the short terminally offset portions of the levers 16. Such a standard 21 is positioned at the front of the cylinder 1 adjacent each end thereof and as they are similar only one is shown and described. This trip 20 is positioned in the path of traverse of the lever 16 in its movement with the cylinder 1. The arm 22 projects from the standard 21 in spaced relation to the arm or trip 20. This arm 22 functions as a means positively to remove the leader from the recess 4 after it has been unlatched through the agency of the trip 21. While any suitable means may be used therefor, this has been found effectively to achieve the purpose. The arm 22 engages the end of the leader extending beyond the cylinder recess and by means of its angled relation to the path of the leader end functions as a cam surface to cause the leader to move from the recess. An arm 23, having spaced relation to the cam arm 22, receives the end of the leader 5. The position and angle of these two projecting arms 23 of the similar and opposed standards 21 are such that the leader is received thereupon. In this embodiment of the invention means are provided to co-operate with the receivers immediately to engage and remove the leader therefrom, pulling the attached rug with the cylinder and against the cleaning action of the revolving brushes. This means comprises a pair of similar endless carriers 24, one each passing adjacent the opposed standards 21. Each of these carriers 24 is provided with a plurality of curved hooks 25 which function in their passage by the receivers to engage the respective ends of the leader when positioned thereupon. These carriers 24 are preferably endless chains actuated at the same rate of speed and traveling between sprockets 26 mounted in brackets 27 on the standards 21. The top portions 30 of the arms 22 are offset sufficiently to permit the ends of the leader raised by the carriers to pass thereby. These carriers being positively driven function not only to draw the rug through the cleaning apparatus but also to carry it to a drier formed by two opposed endless chains actuated at a slower rate and traveling, similarly to the carriers, between sprockets 28, one only being necessary to be shown. The drier chains have hooks 25 similar to those of the carriers. Slides 29, formed by the sprocket brackets projecting from the standards 21 offer means for automatically effecting the transfer of the rug-attached leader from the carrier to the drier.

In operation the device is simple and efficient. The rug, placed upon the table 8, has its end stitched or otherwise fastened to

the fabric 6 of the leader. The cylinder is turned until the recess 4 is adjacent the take-off when the leader is inserted therein so that the face of the rug is outwardly presented. The two end latches are then closed. The cylinder is then driven which positively draws the rug around while it is thoroughly brushed by the oppositely driven brushes. After the cylinder, in its rotation, has 10 passed the position shown in Fig. 1, the opposed trips 20 engage the offset portions of the outwardly projecting levers 16 of the latches and cause the latter to be depressed. Overcoming the tension of the springs, the 15 latches are withdrawn from locking position across the respective ends of the cylinder recess. The resultant direction of rug drag holds the leader within the recess until the ends of the leader, projecting outwardly 20 from the recess termini, are engaged by the cam arms 22 which force the leader to drop to the receiver arms 23. The drop gives rise to just sufficient slack in the rug drag to permit the leader ends to ride down the 25 receiver arms. In this position, the leader ends are immediately engaged by the hooks 25 of the moving carrier by which the rug is thereafter positively drawn around the cylinder and against the action of the 30 brushes as before. Conveyed to the top of the carrier, the leader ends are released by the reversal of direction of the hooks 25 and, descending the opposed slides 29, are engaged by the hooks 25 of the drier. It is 35 to be understood that, while this embodiment of the invention is particularly adapted to the cleaning of rugs, with minor changes in structure, carpets and other articles may easily be treated. This device 40 is durable, simple and expeditious in operation. The parts are relatively few and not liable to derangement and the machine is highly efficient even in the hands of unskilled operatives.

45 The construction disclosed herein is illustrative but not restrictive and the same may be modified within the meaning and scope of the claims which follow.

Having fully described my invention, 50 what I claim as new and desire to secure by Letters Patent is:

- 55 1. In a carpet cleaning machine, a movable member, a leader adapted to be attached to a carpet, means for detachably fastening the leader to said member, means to clean said carpet in its traverse with said movable member, and means operable automatically to detach said leader from said member.
- 60 2. In a carpet cleaning machine, a movable member, a leader adapted to be attached to a carpet, means for detachably fastening the leader to said member, means to clean said carpet in its movement with 65 said member, means operable automatically

to detach said leader from said member, and means operable to engage said leader and carry said leader and thereby said detached carpet from said member.

3. In a carpet cleaning machine, a rotatable member, means for detachably fastening the carpet to said member, means for feeding tangentially the carpet to the rotatable member, means to clean said carpet in its movement with said member, and means operable automatically first to detach said carpet from the rotatable member and thereafter detachably to fasten the carpet to a drying instrumentality. 70

4. In a carpet cleaning machine, a driven rotatable member, means coöperating with said rotatable member to clean a carpet positioned on the periphery of said rotatable member, a leader attached to one end of the carpet whereby the carpet end is also presented to the cleaning means, means for detachably securing the leader to the rotatable member whereby the carpet is positively moved by the driven rotatable member and cleaned, a power driven carrier, and means for detaching and thereafter transferring the leader from the rotatable member to said driven carrier whereby the whole carpet is positively moved past the rotatable member and thereby cleaned. 80

5. In a carpet cleaning machine, a rotatable cylinder having its periphery transversely recessed, carpet cleaning means coöperating with said cylinder, a leader secured to one end of a carpet and receivable in said transverse cylinder recess, latching means normally retaining the leader in said recess, means operable upon a predetermined traverse of the rotatable cylinder to unlatch and to remove said leader from the 100 recess, and means to engage said leader and thereafter draw the carpet past the cleaning means whereby the whole carpet is cleaned. 105

6. In a carpet cleaning machine, a rotatable cylinder having its periphery transversely recessed, carpet cleaning means coöperating with said cylinder, a rigid leader receivable in said recess and projecting beyond the ends thereof, said leader having flexible means for securing one end 110 of the carpet thereto whereby said carpet end is also cleaned, latching means carried by the cylinder normally to retain the leader within the recess, tripping means to unlatch the leader at a predetermined point, means 115 to engage the projecting ends of the unlatched leader and positively to remove the leader from the rotating cylinder. 120

7. In a carpet cleaning machine, a rotatable cylinder having its periphery transversely recessed, carpet cleaning means coöperating with said cylinder, a rigid leader receivable in said recess and projecting beyond the ends thereof, said leader having 125 flexible means for securing one end of the 130 carpet thereto.

carpet thereto whereby said carpet end is also cleaned, latching means carried by the cylinder normally to retain the leader within the recess whereby the carpet is positively moved past the cleaning means by the rotating cylinder, tripping means to unlatch the leader at a predetermined point, means to engage the projecting ends of the unlatched leader positively to remove the leader from the cylinder recess, means to receive the ends of the leader and driven means coöperating with the receiver to engage and to carry the leader whereby the carpet is positively drawn past the cleaning means and carried therefrom.

8. In a carpet cleaning machine, a rotatable cylinder, carpet cleaning means coöperating with said cylinder, a leader having means for securing one end of a carpet thereto, means for fastening the leader to the cylinder, whereby the carpet is positively moved past the cleaning means, similar standards positioned one at each end of said rotatable cylinder, each of the similar standards having arms projecting in spaced relation therefrom and functioning at a predetermined point in the movement of the cylinder successively to unlatch, remove and receive the leader from said cylinder, and driven means coöperating with the receiving arms of the standards to engage and carry the leader whereby the carpet is positively drawn past the cleaning means and carried therefrom.

9. In a carpet cleaning machine, a rotatable cylinder, carpet cleaning means coöperating with said cylinder, a rigid leader having means for securing a carpet end thereto, means for latching the leader to the cylinder, means to unlatch the leader at a predetermined point in the rotation of the cylinder and thereafter to remove the leader from the cylinder, a slideway to receive each end of the removed leader to convey the leader from the cylinder, and a carrier to engage the end portions of the conveyed leader.

10. In a carpet cleaning machine, a driven rotatable member, carpet cleaning means coöperating with said member, a rigid leader having means for securing a carpet end thereto, means for detachably securing the leader to the rotatable member whereby the carpet is positively moved by said member and cleaned, a power driven carrier having means to engage the ends of the leader, means for detaching and thereafter transferring the leader from the rotatable member to the carrier whereby the whole carpet is positively moved past the rotatable member and thereby cleaned, said carrier being movable to raise and thereafter to release the leader at a predetermined point, an inclined slideway to receive the ends of the released leader, a driven drier adjacent the lower end of said slideway to engage and convey the leader and attached carpet.

11. In a carpet cleaning machine, a rotatable member, means for detachably fastening the carpet to said member, means to clean said carpet in its movement with said member, means operable automatically to detach and remove said carpet from the member, means operable automatically to engage and carry said removed carpet and thereafter to release said carried carpet, and means operable automatically to receive and carry said released carpet whereby the carpet is dried.

12. In a carpet cleaning machine, a rotatable cylinder, means for detachably fastening the leading end of a carpet to the periphery of said cylinder, means operable after a partial rotation of said cylinder to detach the leading end of the carpet from the cylinder, means to engage the detached leading end of the carpet and thereafter draw the carpet past the cylinder, and means for cleaning the carpet in its traverse with and past the cylinder.

In testimony whereof, I have signed my name to this specification.

THOMAS J. YATES.
